J. R. HAMILTON,
DRY VALVE FOR AUTOMATIC SPRINKLED SYSTEMS,
APPLICATION FILED NOV. 4, 1913.

1,241,847.

Patented Oct. 2, 1917.

UNITED STATES PATENT OFFICE.

JOHN R. HAMILTON, OF YONKERS, NEW YORK, ASSIGNOR TO AUTOMATIC SPRINKLER COMPANY OF AMERICA, OF NEW YORK, N. Y., A CORPORATION OF NEW YORK.

DRY VALVE FOR AUTOMATIC SPRINKLER SYSTEMS.

1,241,847.

Specification of Letters Patent.

Patented Oct. 2, 1917.

Application filed November 4, 1913. Serial No. 789,134.

To all whom it may concern:

Be it known that I, JOHN R. HAMILTON, a citizen of the United States, and resident of Yonkers, Westchester county, New York, 5 made a certain new and useful Invention Relating to Dry Valves for Automatic Sprinkler Systems, of which the following is a specification, taken in connection with the accompanying drawing, which forms 10 part of the same.

This invention relates especially to dry valves adapted for use with dry pipe automatic sprinkler systems, these valves preferably having the sprinkler connection and 15 water supply connection substantially in line so that when the water valve and air valve are opened under emergency conditions the water has a substantially straight flow passage through the valve. The valves are preferably provided with loose compensating connections which may comprise a reducing-lever loosely pivoted or linked to one of the valves such as the water valve and acted on by a suitable weight so that the valves are 20 under normal conditions held on their seats and the desired proportionate pressure exerted thereon regardless of any slight irregularities in dimensions or construction of parts because of the compensating character 25 of the interposed connections which under emergency conditions are largely or completely removed from the path of flow through the valve casing.

In the accompanying drawings showing 30 in a somewhat diagrammatic way an illustrative embodiment of this invention.

Figure 1 is a vertical section showing the parts in normal position; and

Fig. 2 is a similar view with the parts of 40 the valve in emergency position.

This device may as indicated in the drawings comprise a suitable casing 1 of cast iron or the like which may consist of a main casing 5 inclosing the valve chamber proper and the auxiliary casing or hood inclosing 15 the discharge chamber 24 which may be separated from the main chamber by a diagonal partition in which the inclined air valve seat 31 may be mounted. The casing 20 may be formed with any suitable water supply connection, such as 20, adapted to be connected to the water supply pipe for the sprinkler system and the auxiliary casing or hood is preferably formed with a suitable sprinkler connection such as 3 substantially 25 in line with the water supply connection, so that a substantially straight flow passage is thus provided between these connections when the air valve is open. If desired, a removable cover 2 may be mounted on the 30 hood for inspection or adjustment purposes and a setting opening may be provided in the casing which may be closed by a hinged or otherwise removable door 25 of any suitable construction, so that the internal mechanism 35 may be readily reset or inspected. The air valve 4 coöperating with the valve seat 31 may be of brass or other suitable metal of any suitable construction comprising, if desired, a soft or somewhat yieldable 40 metallic packing engaging the valve seat and may be pivoted about the air valve hinge or pin 8 in the casing, a considerable amount of play being preferably provided in this pivotal connection so as to promote 45 the proper coöperation between this valve and its seat. The air valve is thus mounted within the hood so that when open it can move back into substantially vertical position, as shown by the dotted lines in Fig. 1 50 while its loose connections with the other parts within the casing may then project through the opening in the inclined valve seat and partition. Any suitable form of 55 loose connections may be used for this purpose comprising any suitable pin and slot connection with the air valve, such for example, as the enlarged slot 6 of the somewhat elongated oval shape indicated which may be formed in the stem or projection of 60 the air valve which may as indicated normally extend through the seat. These connections may comprise one or more suitable lifting levers, such as 7, which may swing about the lifting lever pivot 9 in the casing and 65 be formed with a valve pin 28 within the slot 6 on the air valve stem, it being, of course, understood that if desired this lifting lever may be formed of two spaced parts 70 connected by the pivot 9 and pin 28 and 75 which are sufficiently separated to allow the coöperating parts, such as the end of the

air valve stem to pass freely between them. The compensating connections may also comprise a reducing lever, such as 14, having a lifting pin 29 which may engage a 5 suitable recess, such as 30, in the lifting lever, this recess being preferably so shaped as to exert an alining action on this pin and insure the proper longitudinal position of the reducing lever when the holding force 10 is exerted upon it as by any suitable balance weight. This reducing lever is preferably loosely connected or linked to the water valve 19 as by one or more interposed links 21 which are preferably nearly or substantially 15 vertical or perpendicular to the face of the water valve under normal holding conditions and which may be in the form of two similar link members 21 on the two sides of the reducing lever and which may have 20 their ends permanently connected by the link pins 22, 23 coöperating with suitable enlarged holes in the reducing lever and water valve which may be loosely pivoted about the water valve hinge or pin 18 in the 25 bracket 17. The balance weight of any suitable form, such as 10, may with advantage be pivoted within the casing so as to swing, for instance, about the weight pivot 12 and the weight contact or pin 13 extending between the two separated portions of this 30 heavy weight may engage the end of the reducing lever 14 so as to exert the proper pressure on the two valves and hold the striker 11 which may be in the form of a reduced neck or bridge connecting the two 35 parts of the cast iron or other balance weight considerably out of contact with the reducing lever under normal conditions.

Under normal holding conditions the 40 parts of the valve are in substantially the position shown in Fig. 1 in which the balance weight which may amount to 40 or 50 pounds more or less can exert through the loose compensating connections a closing 45 force or pressure in the neighborhood of 200 pounds more or less to the square inch of its working face, tending to hold the water valve closed, while at the same time an opening force of something like 10 pounds 50 to the square inch is exerted on the air valve tending to open it unless resisted by the usual air pressure in the connected sprinkler distributing system. This loosely pivoted reducing lever and the coöperating connections 55 insure the definite application of the predetermined pressures on these two valves regardless of the exact size of parts, such as length of levers and links, so that there is no need for any screw or other fine manual 60 adjustment in order to bring the valves and connections into proper bearing. When under emergency conditions the air pressure is reduced or released above the air valve the lifting pressure thereon becomes suf-

ficient to open this valve which raises the 65 lifting lever and simultaneously allows the other end of the reducing lever to fall, so that it no longer supports the balance weight. This heavy weight then descends 70 and the striker can thus exert an impact blow on the reducing lever to effectively release the valves and connections and quickly swing the reducing lever and air valve linked thereto out of the flow passage. This action may be facilitated by providing a 75 suitable socket 15 on this reducing lever in such position as to coöperate with the projection or turning stud 16 on the bracket 17, these parts being normally out of contact 80 as shown in Fig. 1, but adapted to be forced 85 into contact by the releasing action described so that under emergency conditions the parts assume the full line position shown in Fig. 2. In this way there is little or no interference with the substantially straight 90 flow passage through the valve, and the water valve and connections secured thereto are definitely held in this position by the balance weight. The valve may be readily re-set after the water has been turned off and 95 drained by opening the setting door 25 and first raising the balance weight into the dotted position shown in Fig. 2 so that its notch 27 is engaged by the setting latch 26 so as to be held up out of the way until the two 100 valves are cleaned and closed and the connections all brought into normal position when the balance weight may be released from the setting latch and lowered after the 105 normal air pressure is put upon the distributing system so as to releasably hold these valves closed so long as this air pressure is maintained in the system, the setting door being of course tightly closed when this setting is completed.

This invention has been described in connection with a number of illustrative embodiments, forms, proportions, numbers, arrangements of parts, and materials, to the details of which disclosure the invention 110 is not of course to be limited, since what is claimed as new and what is desired to be secured by Letters Patent is set forth in the appended claims.

1. In dry valves for automatic sprinkler systems, a valve casing comprising a hood, a water supply connection formed in said casing, a sprinkler connection formed in said hood substantially in line with said water supply connection, a pivoted water 115 valve in said casing to normally close said water supply connection, a pivoted air valve in said hood normally closing access to said sprinkler connection and substantially in line with said water supply and sprinkler 120 connections, a lifting lever pivoted in said casing and having a loose pin and slot connection with said air valve, a reducing lever 125

in said casing having a lifting pin to co-operate with a notch in said lifting lever, a link loosely pivoted to said reducing lever and to said water valve, a balance weight pivoted in said casing and having a weight contact adapted to normally engage said reducing lever adjacent its end to normally hold said water valve closed and exert a reduced lifting action on said air valve, a projecting bracket in said casing and a co-operating socket in said reducing lever adapted to come into contact with said bracket but normally out of contact therewith and a striker on said balance weight normally out of contact with said reducing lever and adapted to exert an impact blow on said reducing lever under emergency conditions to release and open said valves.

3. In dry valves for automatic sprinkler systems, a valve casing comprising a hood, a water supply connection formed in said casing, a sprinkler connection formed in said hood substantially in line with said water supply connection, a pivoted water valve in said casing to normally close said water supply connection, a pivoted air valve in said hood normally closing access to said sprinkler connection and substantially in line with said water supply and sprinkler connections, a lifting lever pivoted in said

said air valve, a reducing lever in said casing to co-operate with said lifting lever, a link connecting said reducing lever to said water valve, a balance weight in said casing and having a weight contact adapted to normally engage said reducing lever to normally hold said water valve closed and exert a reduced lifting action on said air valve, a projecting bracket in said casing and a striker on said balance weight normally out of contact with said reducing lever and adapted to exert an impact blow on said reducing lever under emergency conditions to release and open said valves.

65 70 75 80 85

4. In dry valves for automatic sprinkler systems, a valve casing comprising a water supply connection and a sprinkler connection, a pivoted water valve in said casing to normally close said water supply connection, a pivoted air valve normally closing access to said sprinkler connection substantially in line with said water supply and sprinkler connections, a lifting lever pivoted in said casing and having a loose pin and slot connection with said air valve, a compensating reducing lever in said casing having a lifting pin to co-operate with an alining recess in said lifting lever, a link connection loose between said reducing lever and said water valve, a balance weight pivoted in said casing and having a weight contact adapted to normally act on said reducing lever adjacent its end to normally hold said water valve closed and exert a predetermined reduced lifting action on said air valve, a projecting bracket in said casing and a co-operating socket in said reducing lever adapted to come into contact with said bracket but normally out of contact therewith, and a striker on said balance weight normally out of contact with said reducing lever and adapted to exert an impact blow on said reducing lever under emergency conditions to release and open said valves and to swing said reducing lever and water valve around said bracket and substantially out of line with said sprinkler and water supply connections.

90 95 100 105 110

5. In dry valves for automatic sprinkler systems, a valve casing comprising a water supply connection and a sprinkler connection, a water valve in said casing to normally close said water supply connection, an air valve normally closing access to said sprinkler connection substantially in line with said water supply and sprinkler connections, a lifting lever pivoted in said casing and having a loose pin and slot connection with said air valve, a compensating reducing lever in said casing having a lifting pin to co-operate with an alining recess in said lifting lever, a link connection loose between said reducing lever and said water valve, a balance weight pivoted in said cas-

115 120 125

- ing and having a weight contact adapted to normally act on said reducing lever adjacent its end to normally hold said water valve closed and exert a predetermined reduced 5 lifting action on said air valve, a projecting bracket in said casing and a striker on said balance weight normally out of contact with said reducing lever and adapted to exert an impact blow on said reducing lever under 10 emergency conditions to release and open said valves and to swing said reducing lever and water valve substantially out of line with said sprinkler and water supply connections.
- 15 6. In dry valves for automatic sprinkler systems, a valve casing comprising a water supply connection and a sprinkler connection, a water valve in said casing to normally close said water supply connection, 20 an air valve normally closing access to said sprinkler connection substantially in line with said water supply and sprinkler connections, a lifting device in said casing and having a loose pin and slot connection with 25 said air valve, a compensating reducing lever in said casing having a lifting pin to coöperate with said lifting device, a link connection in said casing and adapted to normally act on said reducing lever to 30 normally hold said water valve closed and exert a predetermined reduced lifting action on said air valve, a projecting bracket in said casing and a striker on said balance weight normally out of contact with said 35 reducing lever and adapted to exert an impact blow on said reducing lever under emergency conditions to release and open said valves and to swing said reducing lever and water valve substantially out of line with said sprinkler and water supply 40 connections.
7. In dry valves for automatic sprinkler systems, a valve casing comprising a water supply connection and a sprinkler connection, 45 a water valve in said casing to normally close said water supply connection, and air valve normally closing access to said sprinkler connection substantially in line with said water supply and sprinkler connections, a lifting device in said casing and having a loose pin and slot connection with said air valve, a weight and a compensating reducing lever in said casing having a lifting pin to coöperate with said lifting device, a link connection adapted to normally 50 coöperate with said reducing lever to normally hold said water valve closed and exert a proportionately reduced lifting action on said air valve.
- 55 8. In dry valves for automatic sprinkler systems, a valve casing comprising a water supply connection and a sprinkler connection, a water valve in said casing to normally close said water supply connection, 60 an air valve normally closing said sprinkler connection, a lifting device secured in said casing and having a loose pin and slot permanent connection with said air valve, an automatically compensating reducing lever in said casing having a lifting pin to coöperate with an alining recess in said lifting device, a link loosely pivoted to said reducing lever and to said water valve, a balance weight pivoted in said casing and having a weight contact adapted to normally act on 65 said reducing lever adjacent its end to normally hold said water valve closed by the effective component of said weight exerted thereon and to exert a reduced lifting action 70 on said air valve.
- 80 9. In dry valves for automatic sprinkler systems, a valve casing comprising a water supply connection and a sprinkler connection, a water valve in said casing to normally close said water supply connection, 85 an air valve normally closing said sprinkler connection, a lifting device secured in said casing and having a loose connection with said air valve, an automatically compensating reducing lever in said casing to coöperate with said lifting device, a link pivoted to said reducing lever and to said water valve, a balance weight pivoted in said casing and having a weight contact adapted to normally act on said reducing lever adjacent its 90 end to normally hold said water valve closed by the effective component of said weight exerted thereon and to exert a proportionately reduced lifting action on said air valve.
- 100 10. In dry valves for automatic sprinkler systems, a valve casing comprising a water supply connection and a sprinkler connection, a water valve in said casing to normally close said water supply connection, an air valve normally closing said sprinkler connection, a lifting device secured in said casing and having a loose connection with said air valve, an automatically compensating reducing lever in said casing to coöperate with said lifting device, a connection between said reducing lever and said water valve, a balance weight pivoted in said casing and adapted to normally act on said reducing lever to normally hold said water valve closed and exert a proportionately reduced lifting action on said air valve.
- 105 11. In dry valves for automatic sprinkler systems, a valve casing comprising a water supply connection and a sprinkler connection, a water valve normally closing said water supply connection, an air valve normally closing said sprinkler connection and loose compensating connections between said air valve and said water valve and comprising a lifting lever pivoted in said casing and connected to said air valve, a reducing lever loosely connected to said water valve.
- 110 120 125

- and coöperating with an alining recess in said lifting lever, a balance weight pivoted in said casing and adapted to normally act on said reducing lever to hold said water valve closed and exert a reduced lifting action on said air valve and a striker on said weight adapted to exert an impact blow on said connections and open said water valve.
12. In dry valves for automatic sprinkler systems, a valve casing comprising a water supply connection and a sprinkler connection, a water valve normally closing said water supply connection, an air valve normally closing said sprinkler connection and loose compensating connections between said air valve and said water valve and comprising a lifting device in said casing connected to said air valve, a reducing lever loosely connected to said water valve and coöperating with an alining recess in said lifting device, a balance weight pivoted in said casing and adapted to normally act on said reducing lever to hold said water valve closed and exert a reduced lifting action on said air valve and a striker on said weight adapted to exert an impact blow on said connections and open said water valve.
13. In dry valves for automatic sprinkler systems, a valve casing comprising a water supply connection and a sprinkler connection, a water valve normally closing said water supply connection, an air valve normally closing said sprinkler connection and loose compensating connections between said air valve and said water valve and comprising a lifting device in said casing connected to said air valve, a reducing lever loosely connected to said water valve and coöperating with said lifting device, a balance weight adapted to normally act on said reducing lever to hold said water valve closed and exert a proportionately reduced lifting action on said air valve.
14. In dry valves for automatic sprinkler systems, a valve casing comprising a water supply connection and a sprinkler connection, a water valve normally closing said water supply connection, an air valve normally closing said sprinkler connection and loose compensating connections between said air valve and said water valve and comprising a reducing lever loosely connected to said water valve and having a self alining connection with said air valve, a balance weight pivoted in said casing and adapted to normally act on said reducing lever to hold said water valve closed and exert a reduced lifting action on said air valve and a striker on said weight adapted to exert an impact blow on said connections and open said water valve.
15. In dry valves for automatic sprinkler systems, a valve casing comprising a water supply connection and a sprinkler connection, a water valve normally closing said water supply connection, an air valve normally closing said sprinkler connection and
- tion, a water valve normally closing said water supply connection, an air valve normally closing said sprinkler connection and loose compensating connections between said air valve and said water valve and comprising a reducing lever loosely connected to said water valve and having a self alining connection with said air valve and a balance weight adapted to normally act on said reducing lever to hold said water valve closed by the effective component of said weight exerted thereon and to exert a proportionately reduced lifting action on said air valve.
16. In dry valves for automatic sprinkler systems, a valve casing comprising a water supply connection and a sprinkler connection, a water valve normally closing said water supply connection, an air valve normally closing said sprinkler connection and loose compensating connections between said air valve and said water valve and comprising a reducing lever loosely connected to one of said valves and a coöperating balance weight to hold said water valve closed by the effective component of said weight exerted thereon and to exert a proportionately reduced lifting action on said air valve.
17. In dry valves for automatic sprinkler systems, a valve casing comprising a water supply connection and a sprinkler connection, a water valve normally closing said water supply connection, an air valve normally closing said sprinkler connection and loose compensating connections between said air valve and said water valve and comprising a balance weight to hold said water valve closed by the effective component of said weight exerted thereon and to exert a reduced lifting action on said air valve.
18. In dry valves for automatic sprinkler systems, a casing having a water member normally under the pressure of the water supply to the system, an air member normally under the pressure of the air from the distributing system and compensating connections between said air member and said water member and comprising a reducing lever to exert predetermined proportionate forces on said water member and said air member.
19. In dry valves for automatic sprinkler systems, a valve casing having a water valve normally controlling the water supply to the system, an air member normally under air pressure from the distributing system and compensating connections between said air member and said water valve and comprising a balance weight and a connected reducing lever to hold said water valve closed solely by the effective component of said weight exerted thereon and to exert a proportionately reduced force on said air member.

20. In dry valves for automatic sprinkler systems, a valve casing having a water valve normally controlling the water supply to the system, an air member normally under air pressure from the distributing system and compensating connections between said air member and said water valve and comprising a balance weight to exert force on

said air member and to hold said water valve closed solely by the effective force exerted thereon by said weight.
